UNITED STATES PATENT OFFICE

147,371

DESIGN FOR A TOMBSTONE

Sylvia G. McNatton, Muscatine, Iowa

Application March 26, 1946, Serial No. 127,970

Term of patent 3½ years

(Cl. D79—2)

To all whom it may concern:

Be it known that I, Sylvia G. McNatton, a citizen of the United States, residing at Muscatine, in the county of Muscatine and State of Iowa, have invented a new, original, and ornamental Design for a Tombstone, of which the following is a specification, reference being had to the accompanying drawing, forming a part thereof.

I claim:

The ornamental design for a tombstone, as shown.

SYLVIA G. McNATTON.
